BREECHBLOCK HAVING A TIMING
CIRCUIT SWITCH

Frank E. Knight, Philadelphia, Howard M. Wilde, Feasterville, and Joseph W. Heaney, Philadelphia, Pa., assignors to the United States of America as represented by the Secretary of the Army

Filed May 24, 1965, Ser. No. 458,521

3 Claims. (Cl. 89—17)

The invention described herein may be manufactured and used by or for the Government for governmental purposes without the payment to us of any royalty thereon.

This invention relates to a breechblock for use with ammunition test firing apparatus.

An object of this invention is to provide a breechblock for use with ammunition test firing apparatus including an electrical timing circuit, which breechblock comprises means for accurately determining the instance a firing pin makes firing contact with the primer of a round of test ammunition.

Another object of this invention is to provide a breechblock of the above type which can be used to fire various ammunitions having differing depths of primer penetration requirements and still provide an accurate determination of the instant of firing contact with the primers of a round of test ammunition.

A further object of this invention is to provide a breechblock of the above type wherein the next preceding object is accomplished through a simple external adjustment.

Still another object of the present invention is to provide a breechblock of the character described wherein a hammer member and a contact pin form conductors in an electrical timing circuit which closes when the hammer engages the pin after the hammer acts to move a firing pin a prescribed distance equal to the depth of primer penetration required with a given round of ammunition.

Further objects of the invention will in part be obvious and will in part appear hereinafter.

The invention accordingly comprises the apparatus possessing the construction, combination of elements and arrangement of parts which are exemplified in the following detailed disclosure, and the scope of the application of which will be indicated in the claims.

For a fuller understanding of the nature and objects of the invention, reference should be had to the following detailed description taken in connection with the accompanying drawings wherein:

FIG. 1 is a longitudinal view partly in cross-section of a breechblock embodying the present invention, showing also portions of a typical ammunition test firing apparatus in phantom outline and showing the breechblock in a cocked or ready position;

FIG. 2 is a view similar to FIG. 1, but showing the inventive breechblock in its inactive position;

FIG. 3 is a view taken along the line 3—3 of FIG. 2;

FIG. 4 is a portion of FIG. 2 partially sectioned to show the relationship of parts when the breechblock embodying the present invention is in its firing position.

Referring to the drawings, in which like reference characters refer to like parts throughout the various figures, and referring particularly to FIGS. 1 and 2, 10 represents the breechblock as a whole and illustrates a single embodiment of the present invention. The breechblock 10 contains all electrically conductive parts except where otherwise specified. The body 12 of the breechblock 10 is basically cylindrical in form and is adapted to be assembled with parts of ammunition test firing apparatus. The body 12 has a centrally disposed bore 14 therein. The bore 14 extends through the body 12 and

2

forms an open rearward end portion of the body 12 for insertion of a cocking bar 16, the function of which will become apparent further on in this description. The forward end portion of the bore 14 is closed by members 5 which will be described hereinafter.

A hammer 18 is pivotally mounted in the bore 14 and is held therein by means of a pin 20. The pin 20 is mounted in an appropriate passageway provided in the body as shown in FIG. 3, and passes through an opening 10 in the lower end portion of the hammer 18. The lower end of the hammer 18 abuts the upper end of a housing 22 which contains a helical coil spring 24 in compression. The spring 24 is fixed with respect to the body 12 by means of a pin 26 passing through the body 12 and a disc 28 or the like fixed to the lower end of the spring 24. The housing 22 contacts the body 12 and is free to slide therein. The spring 24 urges an upwardly directed force against the housing 22 and thence through the housing 22 to the hammer 18. The spring 24 and housing 22 together thus provide power means for driving the hammer 18 forwardly from its cocked position illustrated in FIG. 1.

Fixed to the forward end of the body 12 and forming one part of the bore 14 closing is a plate 30 which carries a spring 32 urged firing pin 34. The firing pin 34 is axially aligned with a nose 35 formed integrally with the hammer 18. When the hammer 18 is released from its cocked position the spring 24 will act to urge the hammer 18 in a forward pivotal movement about the pin 20. 20 The nose 35 will then strike the firing pin 34 to impart forwardly directed movement thereto. This firing relationship is clearly shown in FIG. 4.

Disposed below the plate 30 and forming the remainder of the bore 14 closing is an insert 36 of electrical insulation material, such as Micarta for example. The lower end portion of the insert 36 rests in an opening 38 drilled longitudinally in the forward portion of the body 12. A portion of the lower end of the plate 30 abuts the upper end of the insert 36 to fix it firmly in the opening 38.

The insert 36 carries a contact pin 40 at substantially right angles with the axis of the opening 38. The contact pin is threaded on its outer surface and is in threaded movable relationship with the insert. The forward end of the contact pin 40 is adapted by means of a slot or the like to be screwed into or out of the insert as desired. The rearward end of the contact pin extends into the bore 14 and touches a portion of the hammer 18 when the hammer 18 is in a firing position as shown in FIG. 4. When the hammer 18 is cocked or in an inactive position (as illustrated in FIGS. 1 and 2, respectively) the contact pin 40 becomes and remains spaced therefrom. The contact pin 40 comprises a housing 42 carrying at its rearward end a spring 44 urged ball 46. This permits the hammer 18 to strike the contact pin 40 with resulting movement of the ball 46 against the spring 44. This minimizes the tendency of the hammer 18 to move the contact pin 40 out of the insert 36.

An insulated bushing 48 is fitted into the remainder of the opening 38. A locking screw 50 is disposed in the opening 38 and has its upper end carried by the insert 36 substantially at right angles to the contact pin 40.

When the contact pin 40 is set in its desired orientation with respect to the hammer 18 the locking screw 50 is turned to urge upon and secure the contact pin 40 against movement.

The body 12 is made part of an electrical circuit 52 which would most likely be a timing circuit. The circuit 52 is comprised of electrical wiring 54 suitable to a particular timing circuit application. One end of the wire 54 is connected with the body 12 through a suitable connector. The body 12 is in intimate contact with the hous-

ing 22 which abuts the hammer 18. Thus, the hammer 18 may be considered as one conductor of the circuit 52. The wiring is connected with a power source and timer 56 such as a counter chronograph or the like. The other end of the wiring 54 is firmly attached to the lower end portion of the locking screw 50 which urges against the contact pin 40. The contact pin 40 thus forms the other conductor of the circuit.

In operation, the contact pin 40 position relative to the hammer 18 is adjusted in accordance with the depth of firing pin 34 penetration desired. This depth of penetration is determined by the nature of the primer of the particular round of ammunition being test fired. The urging of the hammer 18 by the spring 24 will cause the firing pin 34 to move a prescribed distance. The depth of penetration for firing a certain round of ammunition might be less than the total firing pin 34 movement. Therefore, if a timing circuit were closed after the full movement of the firing pin an erroneous time of primer penetration could possibly be recorded. By this invention the exact time of firing contact with a given primer is recorded since the timer circuit closes exactly at the time of primer contact.

After the contact pin 40 is set the locking screw 50 is tightened to secure the contact pin 40. The hammer 18 is cocked by means of the cocking bar 16. The timer circuit 52 is turned on and the hammer 18 released to urge the firing pin 34 against the primer of the cartridge 58. At the exact point of firing contact with the primer the hammer 18 engages the contact pin 40 to close the circuit 52 thereby initiating whatever timing test is desired.

Since certain changes may be made in the above apparatus without departing from the scope of the invention herein involved, it is intended that all matter contained in the above description or shown in the accompanying drawings shall be interpreted as illustrative and not in a limiting sense.

We claim:

1. A breechblock for use with ammunition test firing apparatus including an electrical timing circuit, comprising

a body having a bore formed therein; a slideable firing pin in the forward portion of said body; a hammer unit movable within said bore and adapted to be moved rearwardly relative to said body to assume a cocked position, said hammer unit being a part of the electrical timing circuit and constituting a conductor therein;

power means within said bore for propelling said hammer unit in a forwardly direction from said cocked position to strike said firing pin and impart a forwardly directed movement thereto; and

other conducting means carried by said body in the forward portion thereof at a point spaced from said hammer unit in its cocked position and engageable by a portion of said hammer unit after said unit has imparted a prescribed forward movement to said firing pin whereby said electrical circuit is closed.

2. A breechblock for use with ammunition test firing

apparatus including an electrical timing circuit, comprising

a body having a bore formed therein; a slideable firing pin in the forward portion of said body; a hammer unit pivotally movable within said bore and adapted to be pivoted rearwardly relative to said body to assume a cocked position, said hammer unit being a part of the electrical timing circuit and constituting a conductor therein;

power means within said bore for propelling said hammer unit in a forwardly direction from said cocked position to strike said firing pin and impart a forwardly directed movement thereto, and

a contact pin carried by said body in the forward position thereof and insulated therefrom, said pin forming a second conductor in the electrical timing circuit, said pin fixed in space relationship with said hammer unit in its cocked position and engageable by a portion of said hammer unit after said unit has imparted a prescribed forward movement to said firing pin whereby said electrical circuit is closed.

3. A breechblock for use with ammunition test firing apparatus including an electrical timing circuit, comprising

a body having a bore formed therein; a slideable firing pin in the forward portion of said body; a hammer unit pivotally movable within said bore and adapted to be pivoted rearwardly relative to said body to assume a cocked position, said hammer unit being a part of the electrical timing circuit and constituting a conductor therein;

power means within said bore for propelling said hammer unit in a forwardly direction from said cocked position to strike said firing pin and impart thereto a forwardly directed movement;

a bushing carried by said body in the forward portion thereof, said bushing being insulated from said body; a movable contact pin in said bushing, said pin fixed in space relationship with said hammer unit in its cocked position and engageable by a portion of said hammer unit after said unit has imparted a prescribed forward movement to said firing pin; and

a movable locking rod for restraining movement of said contact pin when said pin is positioned as desired, said rod and said pin forming a second conductor in the electrical timing circuit, whereby when said hammer unit contacts said pin the electrical timing circuit is closed.
